UNITED STATES PATENT OFFICE

2,566,461

FOUNDATION GARMENT

Patrick J. Morano, New York, N. Y., assignor to
Even-Pul Foundations, Inc., New York, N. Y., a
corporation of New York

Application October 13, 1947, Serial No. 779,612

1 Claim. (Cl. 2—30)

1 This invention relates to foundation garments of the combined girdle or corset and brassière type, wherein the front lower or band portion of the brassière is separate from and overlaps the upper front portion of the girdle or corset-forming body so that said portions may have relative vertical movement as required when the wearer assumes different postures.

The wearer of an ordinary garment of the above kind is subjected to discomfort, due to pinching of the skin between the overlapping front portions of the garment. An object of the present invention, therefore, is to overcome this objection by providing the front band portion of the brassière with an under-belt that extends downwardly past the upper edge of and under the upper front portion of the body. This belt has the intermediate portion of its upper edge secured to the intermediate portion of the upper edge of the front band portion of the brassière so that the skin of the wearer can not enter between and become pinched by said band portion and the upper front portion of the body. Also, the under belt is elastic in a horizontal direction and acts as a diaphragm-constricting element.

The body may be open from top to bottom midway between the sides thereof, and the edges of the body along the opening may be connected by a lacing or the like so as to provide adjustment as to girth for proper constriction of the body and hips of the wearer. In order to prevent discomfort to the wearer by contact of the lacing and the eyelets therefor with the wearer's skin, a pleat strip is disposed across and under the lacing substantially from top to bottom of the body, said pleat strip having its side edges secured to the body at opposite sides of the opening.

The back of the garment may be of unitary construction and forms the back portions of the brassière and the body, the back portion of the brassière preferably having a V-shaped horizontally yieldable elastic gore at the top and center thereof, and the front and back portions of the body and the front band portion of the brassière having similar yieldable gores that extend from top to bottom thereof. Under each side of the front of the body is a horizontally yieldable elastic constricting belt that is secured at its side edges to the body and extends from near the top to a point shortly above the bottom of said body.

The exact nature of the present invention, as well as other objects and features thereof, will become apparent from the following description when considered in connection with the accompanying drawings, in which:

Figure 1 is a front elevational view of a foundation garment constructed in accordance with the present invention and shown as it appears when in use;

Figure 2 is an enlarged horizontal section taken on the line 2—2 of Figure 1;

2 Figure 3 is a vertical section of the garment taken on the plane of the line 3—3 of Figure 2 and drawn on the smaller scale of Figure 1;

Figure 4 is an enlarged fragmentary horizontal section taken on line 4—4 of Figure 3;

Figure 5 is an enlarged fragmentary vertical section taken on line 5—5 of Figure 3; and,

Figure 6 is a view similar to Figure 3, looking toward the back of the garment.

10 Referring in detail to the drawings, 5 indicates the brassière, and 6 the girdle or corset-forming body of the garment. As indicated at 7, the garment may be open at one side from top to bottom thereof, the edges along this side opening being detachably connected by hook and eye or like fasteners as generally indicated at 8 in Figure 2. However, as is conventional in the art, the side opening need only extend from top to bottom of the brassière, the body 6 being of the closed or

20 step-in type.

The brassière includes a front having an upper portion composed of breast pockets 9 joined at 10 along adjacent side edges, and a lower or band portion B joined at its upper edge to the lower edges of the breast pockets 9 as at 11 and composed of a central inelastic panel 12, narrow inelastic side panels 13, and horizontally yieldable elastic gores 14 interposed between the panel 12 and the panels 13 and extending from top to bottom of the lower or band portion.

25 The body 6 includes a front portion which may be open from top to bottom midway between the sides thereof and therefore composed of two sections whose adjacent edges are provided with

30 eyelets 15 and are adjustably connected by lacing 16 threaded through said eyelets. Each of the sections of the front body portion consists of inelastic panels 17 and 18 and a horizontally yieldable elastic gore 19 interposed between the panels

35 17 and 18 and extending from top to bottom of the section. Each panel 17 has a horizontally yieldable elastic substantially V-shaped gore 20 in the lower portion thereof. The adjacent edge portions of the panels 17 may be provided with suitable stiffening stays as indicated at 21 in Figures 2 and 4.

40 The garment shown also includes inelastic side panels 22 and a unitary back 23 that respectively form the sides and backs of both the brassière and the body 6. One side panel 22 is joined along

45 its front edge to the outer side edges of the adjacent panels 13 and 18 and the adjacent breast pockets 9, and both side panels 22 are joined at their rear edges to the side edges of the back 23

50 as clearly shown in Figure 2, the detachable connection at 7, 8 being provided between the front edge of the other side panel 22 and the adjacent outer edges of the other breast pocket 9, panel 13 and panel 18.

55 60 The back 23, as before stated, forms the backs of the brassière and body 6, and it includes a

relatively wide central inelastic panel 24 that may be provided with suitable stiffening stays 25, and horizontally yieldable elastic gores 26 connecting the side edges of the panel 24 with the rear vertical edges of the side panels 22 and extending from the bottom of the back to the top of the lower portion of the latter which forms the back of the body 6 or to the bottom of the upper portion of said back which forms the back of the brassière. The upper portion of the back 10 has a V-shaped horizontally yieldable elastic gore 27 at the top and center thereof. Suitable shoulder straps 28 are connected to the highest points of the breast pockets and to upward extensions 28 of the back 23.

It will be noted from Figure 5 that the front lower band portion of the brassière is separate from and overlaps the upper front portion of the body 6, so that said portions may have relative vertical movement as required when the wearer assumes different postures. Separating movement of these portions may be yieldingly resisted by means of an elastic loop 29 depending from the bottom and center of the front band portion of the brassière and having a hook 30 on its lower end engageable with the lacing 16, with the loop 29 under slight tension.

In order to prevent discomfort to the wearer by contact of the lacing 16 and eyelets 15 with the wearer's skin, a pleat strip 31 is disposed across and under the lacing substantially from top to bottom of the body 6, said pleat strip having its side edges secured to the front body sections at opposite sides of the front opening of the body as at 32. In practice, the lacing 16 is always in place, but is usually loosened before removing the garment or before donning the same.

The front band portion of the brassière is provided with an under belt U that extends above and below the upper edge of and under the upper front portion of the body 6 and that is attached at its ends or side edges to the ends or side edges of said front band portion as indicated at 33 in Figures 3 and 4, said belt including a relatively wide central inelastic panel 34, narrow inelastic side panels 35, and horizontally yieldable elastic gores 36 that connect the panel 34 with the panels 35. The upper edge of the central panel 34 is secured to the adjacent lower edge portion of the breast pockets 9 and to the adjacent upper edge portion of the front band portion of the brassière as indicated by the lead line of numeral 11. Thus, the skin of the wearer can not enter between and become pinched by the front band portion of the brassière and the upper front portion of the body 6. As the under belt is elastic in a horizontal direction, it acts as a diaphragm constricting element.

Under each front body section is a horizontally yieldable elastic body constricting belt that is secured at its side edges to the panels 35 adjacent the side edges of the front body sections as indicated at 37. Each of these constricting belts consists of inelastic panels 38 and 39 connected by a horizontally yieldable elastic gore 40 that extends from top to bottom of the body constricting belt. The panels 38 may be provided with suitable stiffening stays 41. Suitable hose supporters 42 are also provided having one end connected to the bottoms of the panels 17 and the other end connected to depending extensions 43 of the panels 38 respectively forming part of the front body portion and the body restricting belts. It will also be apparent that the under

belt for the front band portion of the brassière overlaps the upper portions of these body constricting belts.

When the present foundation garment is to be used, the lacing 16 is loosened and the garment is then donned with the vertical edges of the garment connected at one side as indicated at 7 by the fasteners indicated at 8. This places the lower front band portion and the under belt of the brassière under tension. The lacing 16 is then tightened until the body 6 is placed under the desired tension, after which the hose supporters are connected to the hose. The garment then properly constricts the diaphragm, waist portion and hips of the wearer, although yielding and permitting freedom of movement as the wearer assumes different postures.

From the foregoing description, it is believed that the construction and advantages of the present invention will be readily understood and appreciated by those skilled in the art. Minor changes in detail of construction illustrated and described, are contemplated, such as fairly fall within the scope of the invention as claimed. For instance, the body of the garment may be laced at the back instead of at the front, or a slide fastener of the "zipper" type may be used instead of lacing.

Having described the invention, what is claimed as new is:

A foundation garment comprising a brassière and a girdle or like body connected thereto, said brassière having a horizontally yieldable partially elastic front lower band portion which is separate from and overlaps the upper front portion of said body outwardly of the latter, and a horizontally yieldable partially elastic under diaphragm-constricting belt for said band portion extending above and below the upper edge of and under the upper front portion of the body, the front portion of said body being open from top to bottom midway between the sides thereof, lacing connecting the edges of the front body sections along said front opening of the body, and a pleat strip disposed across and under the lacing substantially from top to bottom of the body, said pleat strip having its side edges secured to the front body sections at opposite sides of the front opening, each front body section including inelastic panels connected by horizontally yieldable elastic gores extending from top to bottom of said sections, and a horizontally yieldable elastic body constricting belt under each front body section, each body constricting belt being secured at its side edges to the side edges of the associated front body section and extending from near the top of the body section to a point shortly above the bottom of said associated front body section, the diaphragm constricting belt extending under and below the upper portions of said body constricting belts.
